3 Claims. (Cl. 315—138)

This invention relates to electric discharge lighting apparatus. More particularly, this invention relates to lighting apparatus of the type comprising a pair of electric discharge tubes of the type employing an ionizable medium such as gases or vapors, and which ignite by application of a suitable potential without using a switch short-circuiting the tube.

Apparatus of the foregoing type is generally provided with a capacitative impedance in series relationship with one of the tubes and an inductive impedance in series relationship with the other tube in order that a power factor substantially corresponding to unity is obtained. In such apparatus heretofore known in the art, the circuit is arranged so that the tubes, each in series relationship with its respective impedance, are in parallel with each other across the line potential. Such an arrangement, however, has the disadvantage that the apparent power or volt-amperes dissipated by the impedances is much too large. Consequently, the impedance must be overdesigned to handle this power so that it becomes underloaded for the actual or real power dissipated.

The main object of the invention is to reduce the apparent power taken by the impedances.

This and other objects of the invention will be best understood from the following description.

According to the invention one of a pair of said electric discharge tubes is connected in series with a capacitative impedance to a source of potential sufficient to ignite the tube and the other tube is connected in series with an inductive impedance across at least a portion of the capacitative impedance to obtain a potential difference sufficient to ignite the latter tube. With such an arrangement, the apparent power taken by the individual impedances is materially reduced.

The invention will now be described with reference to the accompanying drawing, in which the sole figure shows a circuit diagram of an apparatus according to the invention.

The figure shows an apparatus according to the invention comprising a discharge tube 1 filled with gas or vapor or both, for example, a fluorescent low-pressure mercury vapor discharge tube. The tube 1 is connected by way of a capacitor 2 and an inductor 3 to terminals 4 and 5 of a suitable source of alternating potential (not shown) for operating the tube, e. g., lighting mains at about 220 volts, 50 C. P. S. At the frequency of 50 C. P. S., the capacitative reactance of the capacitor 2 exceeds the inductive reactance of the inductor 3 so that the series-connection of these two elements constitutes a capacitative series-impedance for the tube. The tube itself comprises two activated main electrodes 6, 7 and two conductive ribbon-shaped auxiliary electrodes 8, 9, each of which is connected to one of the main electrodes within the discharge space. The auxiliary electrodes 8, 9 extend parallel to the axis of the tube, within the discharge space, substantially up to the opposite main electrode and are insulated from the latter. Such tubes are often termed tubes with an internal, connected ignition strip. Upon

connection to an appropriate source of potential, a glow discharge is produced between a momentarily negative main electrode, as a cathode, and the nearest part of the auxiliary electrode, as an anode. The glow discharge passes from the main electrode along the auxiliary electrode to the other main electrode heating it to its emission temperature whereby the glow discharge passes over into an arc discharge.

The apparatus further comprises a second discharge tube 10 which is connected by way of an inductor 11 in parallel with the capacitative series impedance 2—3. In the figure, the end 12 of the inductor 11 is connected to the end 13 of the inductor 3. If desired, a tap 14 or the other end 15 of inductor 3 may be used instead of point 13. The tube 10 is also constituted by two activated main electrodes 16, 17 and two internal, connected ignition strips or auxiliary electrodes 18, 19.

If the tubes 1 and 10 are, for example, fluorescent tubes approximately 120 cms. long and approximately 38 mms. in diameter, during normal operation they will dissipate a power of 40 w. with an operating voltage of approximately 110 v. and a current of approximately 440 ma. and 420 ma., respectively. On applying a potential between the junction terminals 4 and 5, first the tube 1 and subsequently the tube 10 will ignite so rapidly that it will only be discernible at a lower potential. During normal operation with a main potential of 220 v., a current of approximately 390 ma. flows through the elements 2 and 3, a voltage of approximately 177 v. occurring across the capacitor 2 and a voltage of about 79 v. occurring across the inductor 3. The operating current of tube 10, approximately 420 ma., flows through the inductor 11 and the voltage across this inductor is approximately 57 v.

With these currents and voltages, the apparent power of the series elements of the tubes is:

Approximately 24 v. a. for inductor 11;
Approximately 30 v. a. for inductor 3; and
Approximately 76 v. a. for the capacitor 2.

The product of the supply potential and the operating current for tube 1 is $220 \text{ v.} \times 0.44 \text{ a.} = 97 \text{ v. a.}$, and for tube 10 is $220 \text{ v.} \times 0.42 = 93 \text{ v. a.}$ Hence, the inductor 11 has an apparent power which is only about 25% of the 93 v. a. The overall apparent power of capacitor 2 and inductor 3 is only about 110% of the 97 v. a.

For purposes of comparison, when the prior art circuit arrangement for the tubes is utilized in which the electrode 17 of tube 10 is not connected to point 20 but to terminal 5, the apparent power of inductor 11 is about 75% of the 93 v. a. and the overall apparent power of the capacitor 2 and the inductor 3 is about 220% of the 97 v. a. Consequently, with the arrangement according to the invention, a substantial reduction of the apparent power taken by the impedances is obtained.

If the supply potential is too low, ignition of tube 10 may not occur. This may be avoided by connecting point 12 of the inductor 11 to a tap, for example, point 14 of the inductor 3.

The term supply potential, as used herein, is to be understood to mean the voltage applied across the leading tube (in this case tube 1) plus its series impedance during operation. As is well-known, this voltage can be given any predetermined value by means of a transformer, for example, if the mains voltage is too low.

As tubes striking without using a switch short-circuiting the tube, besides the aforesaid tubes comprising one or two ignition strips, any tube which is ignited directly by the supply potential or is provided with means for reducing the ignition voltage, for example, by heating the electrodes of the tube to their emission temperature with the aid of transformers, or by increasing the voltage across

the tube with the use of a reactive impedance connected in parallel with the tube, may be used in the apparatus according to the invention.

While the invention has been described in connection with specific examples and in specific application, other modifications thereof will be readily apparent to those skilled in the art without departing from the invention as defined in the appended claims.

What I claim is:

1. An electric discharge apparatus comprising a pair of electric discharge tubes including a first and second tube each having an ionizable gaseous medium and having the characteristic of igniting without using a switch short-circuiting the tube upon application of a given supply potential thereto, a capacitative impedance connected in series relationship with said first tube, said capacitative impedance comprising a capacitor and an inductor connected in series, an inductive impedance connected in series relationship with said second tube, means for connecting said series-connected second tube and inductive impedance in parallel relationship with at least said capacitor and a portion of said inductor, and means for applying said given potential across said first tube and said capacitative impedance.

2. An electric discharge apparatus comprising a pair of electric discharge tubes including a first and second tube each having an ionizable gaseous medium and having the characteristic of igniting without using a switch short-circuiting the tube upon application of a given supply potential thereto having a frequency of about 50 C. P. S., a capacitative impedance connected in series relationship with said first tube, said capacitative impedance comprising a capacitor and an inductor connected in series, an inductive impedance connected in series relationship with said second tube, means for connecting said series-connected second tube and inductive impedance in parallel relationship with at least said capacitor and a portion of said inductor, and means for applying said given potential across said first tube and said capacitative impedance.

5 4
tive impedance, said inductive impedance having a value at which it takes an apparent power not more than 0.7 times the product of said supply potential and the current of said second tube, said capacitative impedance having a value at which it takes an apparent power not more than 2.1 times the product of said supply potential and the current of said first tube.

10 3. An electric discharge apparatus comprising a pair of electric discharge tubes including a first and second tube each having an ionizable gaseous medium and having the characteristic of igniting without using a switch short-circuiting the tube upon application of a given supply potential thereto having a frequency of about 50 C. P. S., a capacitative impedance connected in series relationship with said first tube, said capacitative impedance comprising a capacitor and an inductor connected in series, an inductive impedance connected in series relationship with said second tube, means for connecting said series-connected second tube and inductive impedance in parallel relationship with at least said capacitor and a portion of said inductor, and means for applying said given potential across said first tube and said capacitative impedance, said inductive impedance having a value at which it takes an apparent power of about 0.26 times the product of said supply potential and the current of said second tube, said capacitative impedance having a value at which it takes an apparent power of about 1.1 times the product of said supply potential and the current of said first tube.
